CLAIM

The ornamental design for an arm cradle, as shown and described.

DESCRIPTION

FIG. 1 is a left side perspective view of a first embodiment of an arm cradle in accordance with the present invention; FIG. 2 is a left side view of the first embodiment; FIG. 3 is a right side view of the first embodiment; FIG. 4 is a front view of the first embodiment; FIG. 5 is a rear view of the first embodiment; FIG. 6 is a top view of the first embodiment; FIG. 7 is a bottom view of the first embodiment; FIG. 8 is a left side perspective view of a second embodiment of an arm cradle in accordance with the present invention; FIG. 9 is a left side view of the second embodiment; FIG. 10 is a right side view of the second embodiment; FIG. 11 is a front view of the second embodiment; FIG. 12 is a rear view of the second embodiment; FIG. 13 is a top view of the second embodiment; and, FIG. 14 is a bottom view of the second embodiment.

(Continued)

The broken lines in the drawings depict portions of the arm cradle that form no part of the claimed design.
